US00D826895S

(12) **United States Design Patent** (10) **Patent No.:** **US D826,895 S**
(45) **Date of Patent:** **** Aug. 28, 2018**

(54) **HEADPHONES**

(71) Applicant: **Logitech Europe S.A.**, Lausanne (CH)

(72) Inventors: **Doug Sharp**, Newark, CA (US);
Michael Nolan, Thomastown (IE);
Jimmy Rennick, Dublin (IE); **Cormac O'Conaire**, Dublin (IE)

(73) Assignee: **Logitech Europe S.A.**, Lausanne (CH)

(**) Term: **15 Years**

(21) Appl. No.: **29/599,439**

(22) Filed: **Apr. 3, 2017**

(51) LOC (11) Cl. **14-01**

(52) U.S. Cl.

USPC **D14/205**

(57) **CLAIM**

The ornamental design for headphones, as shown and described.

DESCRIPTION

FIG. 1 is a perspective view of headphones showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and

FIG. 7 is a right side elevational view.

FIG. 8 is a perspective view of both of the ear cups in an uncovered configuration for headphones showing our new design;

FIG. 9 is second perspective view thereof;

FIG. 10 is a third perspective view thereof;

FIG. 11 is a top plan view thereof;

FIG. 12 is a bottom plan view thereof;

FIG. 13 is a front elevational view thereof;

FIG. 14 is a rear elevational view thereof;

FIG. 15 is a left side elevational view thereof; and

FIG. 16 is a right side elevational view.

FIG. 17 is a perspective view of both of the ear cups in a covered configuration for headphones showing our new design;

FIG. 18 is second perspective view thereof;

FIG. 19 is a third perspective view thereof;

FIG. 20 is a top plan view thereof;

FIG. 21 is a bottom plan view thereof;

FIG. 22 is a front elevational view thereof;

FIG. 23 is a rear elevational view thereof;

FIG. 24 is a left side elevational view thereof; and,

FIG. 25 is a right side elevational view.

The broken lines shown in the figures form no part of the claimed design.
